A. A. Ohler

By Robt Robtfield

UNITED STATES PATENT OFFICE.

ALBERT A. OHLER, OF PAINESVILLE, OHIO.

INDICATOR FOR ALARM CLOCKS.

Application filed September 28, 1923. Serial No. 665,301.

To all whom it may concern:

Be it known that I, ALBERT A. OHLER, a citizen of the United States, residing at Painesville, in the county of Lake and State 5 of Ohio, have invented certain new and useful Improvements in Indicators for Alarm Clocks, of which the following is a specification.

The present invention relates to an indicator device for alarm clocks and has for its 10 object to provide a device of this character which embodies novel features of construction, whereby the user of the clock can readily determine whether or not the control 15 member has been set in the "alarm" or "silent" position, even after the light has been extinguished and there is total or partial darkness in the room, such as would make it otherwise difficult to determine 20 whether the control member has been properly set without again making a light in the room.

Among the objects of the invention is to 25 provide an indicator of this character which is comparatively simple and inexpensive in its construction, which can be applied to the conventional alarm clock mechanism without necessitating any changes in the construction thereof, and which enables the user 30 of the clock to readily determine the position of the alarm control member in the dark either by the sense of feeling or by the sense of sight.

With the above and other objects in view 35 the invention consists in certain combinations and arrangements of the parts as will more fully appear as the description proceeds, the novel features thereof being pointed out in the appended claims.

For a full understanding of the invention 40 reference is to be had to the following description and accompanying drawings, in which:

Figure 1 is a front elevation of a portion 45 of a conventional alarm clock, which is provided with an indicator constructed in accordance with the invention.

Figure 2 is an enlarged plan view of the 50 portion of the clock periphery upon which the indicator is mounted, the said portion of the clock being developed or flattened out to simplify the showing of the invention.

Figure 3 is a sectional view on the line

3—3 of Figure 2, looking in the direction of the arrows. 55

Figures 4 and 5 are views similar to Figure 2, showing modified forms of the invention.

Corresponding and like parts are designated on all of the views of the drawings 60 and referred to throughout the following description by like reference characters.

Referring to the drawings, the reference character A designates a conventional form of an alarm clock. The alarm mechanism of this clock may be of any suitable or known construction and is controlled by a shut-off member or lever 1, said lever being movable in one direction to what is usually termed the "silent" position, and being movable in the opposite direction to what is usually termed the "alarm" position. When the shut-off member or lever is at the "silent" position the alarm mechanism is disabled and will not be sounded at any time, 75 although when the shut-off member is at the "alarm" position, the alarm will be given at the predetermined time for which it has been set. The foregoing is of the usual and well known construction and no claim to 80 novelty is based thereon.

The shut-off lever 1 is shown as projecting through a slot 2 in the casing and provided with a finger piece 3. A cooperating finger piece and signal member 4 projects 85 outwardly from the casing of the clock at a point adjacent to one end of the slot 2. As shown on Figure 2, the member 4 is located adjacent the "alarm" end of the slot 2, and is in the form of an ear which is stamped 90 from the sheet metal and bent upwardly therefrom. The member 4 has the body portion thereof arranged parallel to the body portion of the finger piece 3 so that the two have an opposed relation and can be readily 95 engaged by the thumb and forefinger of a hand when it is desired to move the shut-off lever into "alarm" position. The signal member 4 is also provided with a lateral flange 100 4^a, and the finger piece 3 has a corresponding lateral flange 3^a and top flange 3^b.

The lateral flanges 4^a and 3^a are arranged so that they will overlap, as indicated by dotted lines on Figure 1, when the shut-off lever is moved to "alarm" position and the top 105 flange 3^b then extends over the top of the

signal member. The two flanges 4^a and 3^a which are visible from the front of the clock may, if desired, be provided with luminous paint as is indicated by the stippling on the drawing.

The user of the clock, knowing that the signal member 4 is at the "alarm" end of the slot can tell by the sense of feeling whether the shut-off lever is at the desired position, since by placing the fingers upon the parts he can readily determine whether the finger piece 3 is against the signal member or spaced therefrom. Where the parts have the luminous paint applied thereto, as previously indicated, the user can readily tell by looking at the clock whether the shut-off lever is at the proper position. If the two patches of luminous paint appear in a spaced relation the shut-off lever is obviously at the "silent" position, although if only one patch of luminous paint is visible the shut-off lever has obviously been moved to "alarm" position, in which position it overlaps and covers the projecting signal member 4. It is thus easy for the user of the alarm clock to determine whether or not the alarm has been set, even after he has retired and the light in the room has been extinguished, so as to leave the alarm clock in total darkness.

A slight modification is shown by Figure 4, in which the signal member 4^c is in the form of a projection which is applied to the clock casing or struck therefrom. The upper end of the shut-off lever is provided with a finger piece 3^c which corresponds in general shape and appearance to the signal member 4^c. Luminous paint may be applied to the members 4^c and 3^c, if desired, and the user of the clock knows that when the members are close together the alarm is set, while when the members are far apart the shut-off lever is in the "silent" position.

A further modification is shown by Figure 5, in which the signal member 4^d is similar to that indicated by Figure 4. The finger piece 3^d projects laterally from the upper end of the shut-off lever and is arranged so that it will extend over the top of the signal member 4^d when the shut-off member is moved to "alarm" position. The members 4^d and 3^d may have luminous paint applied to the top thereof, and this form of device is well adapted for use when the clock will be viewed from the side or top thereof, rather than from the front thereof. The finger piece has an overhanging portion which extends over the signal member when the shut-off lever is in "alarm" position, and

the user can readily tell by feeling of the parts or by looking at them if they are coated with luminous paint, whether the shut-off lever is in the desired position.

While certain forms and embodiments of the invention have been shown for illustrative purposes, it will be understood that many modifications and changes can be made in the details of construction without departing from the spirit of the invention.

Having thus described my invention what I claim as new and desire to secure by Letters Patent of the United States, is:

1. The combination with an alarm clock having an alarm control member movable into "alarm" and "silent" positions, of an indicating means including a finger piece on the control member, an opposed finger piece and signal member adjacent to one end of the path of movement of the control member, and luminous paint on the two finger pieces.

2. The combination with an alarm clock having an alarm control member movable into "alarm" and "silent" positions, of indicating means including a finger piece on the control member, and an opposed finger piece and signal member adjacent to one end of the path of movement of the control member, one of the finger pieces being arranged to overlap and conceal the other finger piece when the control member is at one limit of its movement.

3. The combination with an alarm clock having an alarm control member movable into "alarm" and "silent" positions, of indicating means including a finger piece on the control member, and an opposed signal member arranged adjacent to one end of the path of movement of the control member, the finger piece and signal member being formed with side flanges and one of the side flanges being adapted to overlap and conceal the other side flange when the control member is at one limit of its movement.

4. The combination with an alarm clock having an alarm control member which is movable into "alarm" and "silent" positions, of indicating means including a visible finger piece on the control member and an opposed complementary finger piece and signal member arranged adjacent to one end of the path of movement of the control member, whereby an observer can tell by the distance between the finger piece and signal member whether or not the alarm is set.

In testimony whereof I affix my signature.

ALBERT A. OHLER.
